UNITED STATES PATENT OFFICE.

JOHN CORYDON GIBBS, OF PHILADELPHIA, PENNSYLVANIA.

LID-RAISING DEVICE.

1,107,781.

Specification of Letters Patent. Patented Aug. 18, 1914.

Application filed December 29, 1913. Serial No. 809,194.

To all whom it may concern:

Be it known that I, JOHN CORYDON GIBBS, a citizen of the United States, residing in the city and county of Philadelphia, State of Pennsylvania, have invented a new and useful Lid-Raising Device, of which the following is a specification.

My invention consists of a novel construction of lid raising device, combined with a 10 novel packing device therefor, which is applicable generally to various forms of boxes or receptacles, having tight fitting lids or closures, which require considerable expenditure of force to remove or open, the invention being particularly applicable to receptacles, such as tin boxes, for containing shoe 15 polish and other evaporable compositions which require a tight fitting lid, that will effectually seal the contents of the receptacle 20 from the atmosphere. It will, however, be understood that in the practical use of my invention, I do not limit the same to boxes for the reception of any particular kind of material or composition, but the same is 25 adapted for any kind of boxes or receptacles for the reception of any plastic or semi-plastic material, which may or may not have a tendency to evaporate upon exposure to the atmosphere.

30 By the employment of my invention, I have produced a packed lid raising device, which is particularly adapted for use in connection with all boxes or receptacles for evaporable compositions, having tight fitting lids or closures, which can be quickly 35 and positively removed without damage or distortion of either the lid or the receptacle, thereby enabling the lid to be replaced with a tight and even fit repeatedly until all the 40 contents of the box or receptacle have been utilized.

For the purpose of illustrating my invention, I have shown in the accompanying drawing one form thereof which is at present 45 preferred by me, since the same will be found in practice to give satisfactory and reliable results, although it is to be understood that the various instrumentalities of which my invention consists can be variously arranged and organized, and that my invention is not limited to the precise arrangement and organization of these instrumentalities as herein shown and described.

50 Figure 1 represents a perspective view showing the exterior or manually operated portion of my novel construction of lid rais-

ing device. Fig. 2 represents a section on line $x-x$, Fig. 1, showing the relation of the packing device to the lid raising cam and its adjuncts. Fig. 3 represents a section on line $y-y$, Fig. 2. Fig. 4 represents a perspective view of the cam and its operating stem and their adjuncts, in detached position.

Similar numerals of reference indicate corresponding parts in the figures.

Referring to the drawings:—1 designates a box or receptacle, to which my invention is applicable, the same comprising the bottom or body portion 2 and the tight fitting lid or cover portion 3, my invention being shown in the present instance as adapted, in one embodiment thereof, to a box for shoe polish or similar evaporable compositions, which require a lid fitting tight enough to effectually seal the contents of the receptacle 75 from the action of the air. The bottom or body portion 2 may be constructed, as is customary, with the base 4, and the upright, annular, square or other shaped wall 5, which terminates in the top edge 6, having, 80 if desired, the reversely turned portion 7, although the latter may be omitted, if desired, and the wall 5 may or may not have an annular strengthening bead 18, since this *per se* forms no part of my invention.

In the case of blacking boxes, to which my invention is especially applicable, a very tight fit is produced, when the lid is forced down into place, and as the material of which the lid and box body are composed is somewhat pliable, an even fit is obtained between the lid and receptacle that seals the contents from the air, but disengagement of the lid is frequently difficult because of the binding action between the contiguous 95 flanges and the sticking produced by the composition lodging between said flanges, all of which objections are provided for or obviated by the use of my invention, now to be referred to.

The lid or cover 3, to which my invention is applicable, comprises the top 8, having the depending flange 9, which is adapted to engage the outer peripheral portion of the edge 6, said depending flange 9 having the 105 outwardly bulged portion or hollow boss or protuberance, 10, within which is contained a packing or filling 11 of suitable packing material, through which passes the stem 12, having secured to its inner portion the cam 110 13 having the operative cam face 14, which is adapted to normally rest upon the top

edge 6 of the box body, as will be understood from Fig. 3. The outer end 15 of the stem 12 is preferably slightly enlarged and provided with a cut or kerf 16 therein, in which 5 is inserted the finger-piece 17, which can be readily manually operated, whereby the cam 13 can be readily turned, rocked or oscillated from the exterior of the box when it is desired to raise the lid therefrom, the contact 10 of said cam with the top edge 6 of the box body serving to raise the cover 3 therefrom, as is evident. The finger-piece 17 can be pinned, soldered or otherwise secured to the stem 12 or its outer end 15, according to requirements, as will be apparent to those skilled in the art.

I desire to call especial attention to the employment of the packing 11 in connection with the hollow boss 10, said packing being 20 retained in position within said boss by the cam 13, so that it will be apparent that the contents of the closed box will be kept free, by reason of the packing devices, from deterioration, by the action of the atmosphere 25 or other climatic causes, which is very essential in devices of this character, since if the stem 12 is merely loosely inserted in a hole in the flange 9 of the cover, as in prior constructions with which I am familiar, the 30 contents of the box are liable to become affected by the ingress of the air thereto, whereas in my novel construction, no such disadvantages are present. It will furthermore be apparent, that the provision of the 35 hollow boss 10 serves as a handle for the lid, and by the employment of the packing devices 11, retained in position by the cam 13, there can be no leakage of the contents of the box, and soiling of the hands of the user 40 is therefore avoided.

It will be clearly seen from the foregoing that my novel construction of a lid raising device in conjunction with the packing devices employed, operates positively to separate the lid and body of the receptacle, without damaging or distorting either part, so that the operation may be repeated many 45 times, without impairing the tight fit of the lid on the receptacles, which is essential to prevent evaporation or leakage of the 50 contents of the receptacle.

It will now be apparent that I have devised a novel and useful construction of a lid raising device, which embodies the features of advantage enumerated as desirable 55 in the statement of the invention and the above description, and while I have, in the

present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. As an improved article of manufacture, a box cover having a hollow inwardly open 70 boss, packing filling said boss, a stem rotatably mounted in said boss and packing, and a cam on said stem, the inner wall of said cam abutting said packing whereby said packing is retained by said cam within the 75 boss.

2. A box body, a cover for said body having a flange, a hollow boss projecting from said flange, a stem rotatably mounted in said hollow boss, a cam mounted on the inner end 80 of said stem, and projecting beyond the inner wall of said flange to engage the upper edge of the flange of said box body, and packing in said hollow boss, said cam serving to hold said packing in said boss.

3. A box body, a cover for said body having a flange, a hollow boss projecting from said flange, a stem rotatably mounted in said hollow boss, a cam mounted on the inner end 90 of said stem, and projecting beyond the inner wall of said flange to engage the upper edge of the flange of said box body, and packing in said hollow boss, said cam serving to hold said packing in said boss, in combination with a finger-piece secured in 95 the outer end of said rotatable stem, for manually rotating the latter.

4. In a box lid raising device, the combination of a cover flange having a pocket therein, packing material located in said 100 pocket, a stem passing through the outer wall of said pocket and said packing, and having a cam on the inner end thereof, said cam projecting beyond the plane of the inner face of the box cover lid to contact 105 therewith, and serving as the sole means for retaining said packing in position, a finger-piece on the outer portion of said stem, said finger-piece being secured in a slot in the outer portion of said stem.

JOHN CORYDON GIBBS.
